HOSE NOZZLE

Edmund J. Kenney, North Plainfield, N. J.

Application February 11, 1937, Serial No. 125,201

1 Claim. (Cl. 299—131)

This invention relates to improvements in nozzles, and more particularly to nozzles for use upon garden hose.

In the present construction of nozzle used upon garden hose, it is necessary for the user to grasp the hose with one hand while effecting an adjustment of the water stream with the other hand, due to the fact that the stationary base end of the nozzle does not afford the proper hand grip which will permit of the base end of the nozzle to be held stationary during manipulation of the adjusting head. Usually the hose is dirty and touching of the same during adjustment of the nozzle to change the water stream causes the hands of the user to become soiled. It is therefore the main purpose of this invention to provide a hose nozzle in which the base of the nozzle is provided with an elongated spindle body of sufficient length to afford a hand grip for a user, the adjusting head being carried by the outer tip end of the spindle body and being relatively short and stubby so as not to make the nozzle unduly long in length. By such improved construction, it is possible for a user to firmly grasp the spindle body of the nozzle while effecting an adjustment of the water stream, thus making it unnecessary for a user to shift the hand onto the hose.

Another feature of the invention resides in a hose nozzle having a substantially uninterrupted bore which extends from the base inlet end thereof to a point adjacent the discharge orifice which serves to increase the length and force of the water stream emitted from the discharge orifice.

A further feature of the invention is to provide a hose nozzle which is simple of construction, comfortable to hold in the hand of a user, and which is inexpensive of manufacture so as to be within the price range of the conventional hose nozzle now upon the market.

With these and other objects in view, the invention resides in the certain novel construction, combination and arrangement of parts, the essential features of which are hereinafter described in the following specification, are particularly pointed out in the appended claim, and are illustrated in the accompanying drawing, in which:

Figure 1 is a perspective view of the improved hose nozzle.

Figure 2 is a vertical longitudinal sectional view on the line 2—2 of Figure 1, but showing in dotted lines the position of the adjusting head when in fully closed position.

Figure 3 is a vertical transverse sectional view on the line 3—3 of Figure 3.

Figure 4 is a slightly modified form of the invention.

Figure 5 is a vertical transverse sectional view on the line 5—5 of Figure 4.

Figure 6 is a modified form of stuffing box

which is employed for sealing the joint between the spindle body and the adjusting head.

Figure 7 is a vertical transverse sectional view on the line 7—7 of Figure 6.

Like reference characters refer to the same parts throughout the several forms of the invention to be hereinafter described.

Referring to the drawing by reference characters and more particularly to the form of the invention shown in Figures 1 to 3 inclusive, the numeral 19 designates my improved hose nozzle in its entirety and which includes a tubular spindle shaped body 11 having a substantially uninterrupted bore 12 extending lengthwise therethrough. The inlet end of the body 11 is provided with a hose connecting base 13, which is internally screw threaded to facilitate the attachment of the nozzle to one end of a hose. The outer end of the body 11 is reduced in diameter as at 14, and the tip end thereof is provided with an integral valve member 15 which is in the shape of a collar button. The valve member 15 is disposed in axial alignment with the axis of the body 11 for a purpose to be hereinafter appreciated. The tip end of the body 11 is also provided with opposed radially extending discharge passages 16—16 which passages open onto the exterior of the reduced extension 14. The extension 14 inwardly of the passages 16 is screw threaded as at 17 and seated in a recess 18 at the inner end of the screw threaded portion, is a split ring 19, which ring acts to limit the outward turning movement of the control head presently to be described. The outer end of the reduced portion 14 of the body 11 is beveled as at 20 to provide a seat 21 to receive the control head when the same is moved to a fully closed position.

Carried by the reduced extension 14 of the spindle body 11 is a thimble shaped control head 21, the outer closed end of which is provided with a flared discharge orifice 22, the said orifice being disposed in alignment with the axis of the spindle body 11. The orifice 22 is of a size to permit of the passage of the valve member 15 therethrough and the said valve member coacts with the walls of the orifice to regulate the stream of water discharged from the nozzle. The control member 21 is internally screw threaded as at 23 for threading engagement with the thread 17 on the reduced extension 14. The open end of the member 21 is internally screw threaded for threadedly receiving a packing nut 24 and which nut serves to compress a packing ring 25 for sealing the joint between the control head 21 and the reduced portion 14 of the spindle body 11.

By reason of the relative length of the control head 21 and the spindle body 11, it will be seen that the exterior of this spindle body 11 is of a sufficient length to provide a hand grip for a user of the nozzle, and in order to facilitate firm

gripping of the spindle body 11, the exterior of the same is provided with a knurled portion 26.

In practice, the threaded base 13 is attached to the outlet end of a hose and the water from the hose enters the bore 12 and is free to pass to the discharge passages 16 from where the water enters the restricted space between the control head 21 and the tip end of the spindle body, and thence it passes through the restricted discharge orifice 22, the said orifice being regulated as to size by reason of the valve 15. The operator may firmly grasp the nozzle at the knurled portion 26 with one hand and with the fingers of the other hand, he may manipulate the control head 21 to turn the same in order to regulate the stream of water passing through the discharge orifice 22. In order to provide sufficient friction surface on the interior of the control head 21, the said head is provided with a knurled portion 27. When the control head 21 is moved to the limit of its inward movement as shown in dotted lines in Figure 2, the end wall of the said control head seats against the beveled surfaces 20 on the tip end of the spindle body 11. Outward movement of the control head 21 is limited by engagement of the gasket 25 engaging the ring 19.

In Figures 4 and 5 of the drawing, a slightly modified construction has been shown, and wherein the numeral 30 designates a tapered spindle body having a tapered bore 31 extending therethrough. The wide end of the body is provided with a hose attaching base 32, whereas the opposite end is of a substantially uniform diameter. The exterior of the outer tip end of the body 30 is screw threaded as at 33, while opposite sides of the bore 31 inwardly of the tip end are provided with channels 34. The walls of the bore 31 at the tip end are internally screw threaded as at 35 for threadedly receiving the exteriorly screw threaded body 36 of a valve member 37. The inner end of the body 36 is provided with a kerf 38 to facilitate threading of the valve member 37 into and out of the tip end of the body 30. Opposite sides of the threaded body 36 of the valve member 37 are flat as at 39 and are disposed in alinement with the channels 34 to provide outlet passages 39 which communicate with the bore 31 and with the tip end of the spindle body 30. A ring 40 is seated inwardly of the threaded portion 33 for the same purpose as that shown in Figure 2 and previously explained.

Threaded to the tip end of the body 30 is the control head 21 and which is identical in construction to that shown in Figure 2. The parts function in the same manner as previously explained so that a repetition of the entire operation is not deemed necessary. However, it may be stated that the water enters the nozzle through the enlarged end of the tapered bore 31 and flows uninterrupted to the discharge passages 39 from where it leaves the nozzle through the discharge orifice 22 in the control head 21. In this form of the invention I provide diametrically opposed ribs 41 on the spindle body 30 to act as hand grip portions for a user when grasping the nozzle during use. The ribs or wings 41 are the equivalent to the knurled portion 26 hereinbefore mentioned.

In Figures 6 and 7 of the drawing, a slightly different construction of stuffing box has been shown wherein in lieu of the nut 24 an externally

screw threaded ring 42 is threaded to the internally screw threaded portion of the control head 21 for the purpose of maintaining the gasket 25 in position. In view of the fact that the ring 42 is disposed within the open end of the control head 21, spanner openings 43 are provided in the outer sides of the ring to enable a spanner wrench to be applied thereto during turning of the ring 42 relative to the control head 21.

From the foregoing description, it will be seen that I have provided a hose nozzle which includes a stationary body member having a sufficient exposed portion to enable firm gripping of the same by the hand of a user, and which permits the nozzle to be held in one hand while using the other hand to impart a turning movement to the control head 21 when making an adjustment for regulating a stream of water emitted from the discharge end of the nozzle. These parts are so designed and proportioned as to make the nozzle comfortable to the hands of a user and avoid bulkiness and undue length to the nozzle in its entirety.

While I have shown and described what I consider to be the most practical embodiment of my invention, I wish it to be understood that such changes and alterations as come within the scope of the appended claim may be resorted to if desired.

Having thus described the invention, what I claim as new and desire to secure by Letters Patent of the United States, is:—

A hose nozzle comprising in combination, a relatively long tubular spindle-like body having an enlarged hose attaching base at the inner end thereof and also having a reduced cylindrical outer end provided with a restricted discharge outlet, the intermediate portion of the body between said attaching base and reduced outer end constituting a hand grip, a valve element carried by and extending beyond the tip end of said spindle-like body and disposed axially relative thereto, said reduced end of the body including an external threaded portion adjacent the valve element, a relatively short stream control head, internal threads provided on the reduced end of said spindle-like body and threadedly engaging the external threaded portion on said body and having a flared discharge orifice in the outer end thereof and disposed axially with respect to said spindle-like body, the walls of said discharge orifice adapted to coact with said valve element to regulate the stream of water discharged from the nozzle, an annular recess in the exterior of the reduced end of the body at the inner end of the threaded portion thereof, a stop ring seated in said recess, an enlarged internally threaded portion at the inner end of said control head, a shoulder at the inner end of the enlarged internally threaded portion, and a packing gland threaded to the internal threaded portion of the control head and having a working fit on the reduced end of the spindle-like body inwardly of the threaded portion thereof and embodying a packing gasket arranged to constantly abut the inner end of said packing gland and said shoulder and to abut the stop ring when the control head has been turned to the limit of its outward movement, said stop ring operating to compress the gasket when engaged thereby to increase the sealing action of the gasket.
